UNITED STATES PATENT OFFICE.

ALVARO S. KROTZ, OF JANESVILLE, WISCONSIN, ASSIGNOR TO JANESVILLE MACHINE COMPANY, OF JANESVILLE, WISCONSIN, A CORPORATION OF WISCONSIN.

WHEELED IMPLEMENT.

1,205,754.

Specification of Letters Patent. Patented Nov. 21, 1916.

Application filed September 18, 1913. Serial No. 790,487.

To all whom it may concern:

Be it known that I, ALVARO S. KROTZ, a citizen of the United States of America, and resident of Janesville, Rock county, Wisconsin, have invented a certain new and useful Improvement in Wheeled Implements of which the following is a specification.

My invention relates to wheeled implements in general, but more particularly to wheeled plows, and especially those in which the plow is supported by one or more bails, the said bail or bails being in turn mounted on a frame carried by the wheels.

Generally stated, the object of my invention is to provide a novel and efficient wheeled implement of the foregoing general character.

A special object is to provide a wheeled implement having a depth regulating mechanism whereby no provisions for adjustment of the front and rear wheels are necessary, the regulation of the depth, as well as the leveling of the plow, being controlled entirely by a single hand lever, and the said lever forming medium of connection between a foot lift mechanism and the plow or other working element.

Another object is to provide a novel mechanism for causing the plow to enter and leave the ground point first, adapted to permit the rear end of the plow to rise and prevent breakage when the plow point strikes an obstruction, and forming a rear connection between the plow beam and frame.

Another object is to provide a stop device for preventing the plow from jolting up and down when in the ground and under pressure.

A further object is to provide an adjustable connection between the tongue and the front furrow wheel, whereby the position of the tongue relative to the said wheel can be changed when necessary, or maintained at the proper angle, as circumstances may require.

To these and other useful ends my invention consists in matters hereinafter set forth and claimed.

In the accompanying drawings: Figure 1 is a plan of a wheeled plow embodying the principles of my invention. Fig. 2 is an enlarged detail section on line 2—2 in Fig. 1. Fig. 3 is an enlarged perspective of the ad-

justable tongue connection which forms one feature of my invention. Fig. 4 is a land-side elevation of the said plow, showing the land-side wheel removed for convenience of illustration, but dotted in to show the position thereof during operation of said plow. Fig. 5 is a longitudinal section on line 5—5 in Fig. 1, showing the plow leaving the ground, (in full lines) and indicating in dotted lines the position of the plow when it strikes an obstruction, or when it enters the ground. Fig. 6 is a detail section on line 6—6 in Fig. 8. Fig. 7 is a similar section on line 7—7 in Fig. 8. Fig. 8 is an enlarged rear elevation of the raising and lowering means, and also the depth regulating mechanism shown in Fig. 1, showing a portion of the land-side wheel. Fig. 9 is a detail section on line 9—9 in Fig. 8. Fig. 10 is a detail section on line 10—10 in Fig. 7. Fig. 11 is a detail section on line 11—11 in Fig. 6. Fig. 12 is a view similar to Fig. 5, but showing the plow raised out of the ground. Fig. 13 is a view similar to Fig. 8, but showing another form of my invention. Fig. 14 is a section on line 14—14 in Fig. 13. Fig. 15 is a section on line 15—15 in Fig. 14.

As thus illustrated, my invention comprises a body frame A supported horizontally by the front and rear furrow wheels B and C, and by the land-side wheel D. The plow E has a beam e carried on the bail F which is mounted to turn in bearings f and f' on the frame.

The foot lift mechanism comprises a lifting lever G and a depressing lever g rigidly connected together in the manner shown in Fig. 7, and held thus by a bolt g¹ extending from one to the other through the sleeve g² that turns in the top of the bearing 95 bracket f¹ on the frame. The said bracket is formed with a shoulder g³ and a notch g⁴, adapted to be engaged by a spring catch g⁵ on the lever g, whereby the plow is locked down when the lever is as shown in Fig. 7, or up when the levers swing back and the catch engages the notch g⁴. The arm g⁶ is rigid with the lever g, and is connected by a link g⁷ with the arm g⁸, which latter is rigid with a sleeve g⁹ on the straight 105 outer portion f² of the bail.

One feature of my invention comprises the arm g¹⁰ which is rigid with the sleeve g⁹ and which is provided with a set screw g¹¹ for engaging the stop g¹² of the bearing 110

bracket f^1 on the frame. By this construction the downward movement of the arm g^8 is limited, and the weight of the plow, when down, is not on the link g^7 , but on the frame. 5 In this way the foot lift mechanism is relieved of the strain. In other words, the plow is held at a fixed depth, and does not ride out in hard spots, even though the connections involving the link g^7 are more or 10 less loose. The set screw g^{11} takes up the slack or looseness, so to speak, and prevents the plow from jumping up and down. When the plow is down as shown in Fig. 7, the pivotal joints g^{13} , g^{14} and g^{15} are in 15 line, and with the joint g^{14} thus on center, the plow is held down, and the weight of the plow is on the set screw g^{11} , instead of on the link g^7 , when the said screw is properly adjusted. Thus the pressure 20 against the stop g^{12} relieves the strain on the foot lift mechanism, when the plow is in the ground. The screw g^{16} on the link g^7 engages a stop g^{17} on the arm g^8 , to limit the movement of the joint g^{14} toward 25 the rear of the plow.

Another feature of my invention comprises the hand lever H which is rigidly keyed to the bail portion f^2 (see Figs. 8 and 9) and which is provided with a short 30 arm h having three bolt holes h^1 . The arm h^2 is loose on the portion f^2 , but is connected rigidly with the arm h by a bolt h^3 inserted through the middle one of said holes h^1 . The offset axle d is rigid with said arm h^2 , 35 and supports the land-side wheel D . For ordinary purposes this adjustment of the joints is employed; but extreme positions of the plow up and down may be obtained by shifting the bolt h^3 to one of the other 40 holes, and for unusually deep plowing the bolt will be set in the uppermost hole h^1 and for unusually shallow plowing, in the lowermost hole. Thus the hand lever H is available 45 for assisting the lever G in raising the plow out of the ground, and the adjustable connection between this lever and the offset axle of the land-side wheel permits the plow to operate at different depths. But in each 50 case the lever G has the same throw or range of movement.

A further feature of my invention comprises the curved rack arrangement I which is rigid with the sleeve g^9 , which latter is loose on the bail portion f^2 , and a spring 55 catch i on the lever H , said catch being controlled by the usual means on the upper end of said lever. Thus the lever H can be set in different positions relative to the rack I , and this changes the angle of the bail F relative to the arm g^8 , permitting the plow 60 to assume a higher or lower working position. In this way the depth of the furrow is regulated, and as the operation of said lever H serves also to vary the angle of the 65 axle arm h^2 , an arrangement of this character

serves also for leveling the plow. If the depth is not right, when lever H reaches the limit of the rack I , in either direction, then a further adjustment for this purpose is obtained by the holes h^1 and bolt h^3 , in the 70 manner previously explained.

The means for supporting the rear end of the plow, and for causing the plow to enter and leave the ground point first, constitutes an additional feature of my invention. 75

This comprises the member or so-called bail J pivoted to the lower ends of the brackets j , to swing up and down at its upper end. The bracket j^1 on the plow beam is connected by the link j^2 with the upper 80 end of said member J , in the manner shown. Preferably the relative arrangement and proportions are such that the member J never reaches a horizontal position, but always stands at an angle. This is further 85 insured by the stop j^3 on the frame, upon which stop the member J rests when down, being provided with a lateral projection J^1 for engaging said stop. By this provision the downward motion of the member J is 90 caused to cease a little before the bail F reaches its lower position for normal depth. If the plow is then lowered to a greater depth, it will be tilted forward with its 95 point downward. When the plow starts to rise, the link j^2 swings backward a distance before reaching a position which causes the member J to rise, the two elements being relatively formed for this purpose. This enables the plow point to tilt 100 upward, so that the plow comes out of the ground point first, as shown in Fig. 5. As the lifting movement of the plow continues, by downward movement of the lever G , the member J is forced upward and into the 105 position shown in Fig. 12. Preferably, the link j^2 has a projection j^4 at its upper end, which at times will engage the stop j^5 on the member J , as shown in dotted lines in Fig. 5, to limit the upward movement of the rear 110 end of the plow, when it tilts in this direction, as in entering hard ground.

The front and rear wheels B and C have their stems or standards connected by a rod K , in the usual way, whereby the tongue L controls the rear caster wheel C as well as the said front wheel. For this purpose the said rod is secured to a crank arm c on the upper end of the stem or standard c^1 of the rear wheel, and the front end of said rod is arranged to slide in the slot k in the arm k^1 fixed on the upper end of the stem b of the front wheel. This sliding movement of the end of the rod in the slot k is in opposition 120 to the spring k^2 , in the usual manner, and only occurs when the tongue swings to one side.

Another feature of my invention comprises the curved rack k^3 , adapted to be engaged at different points by the spring catch 130

*k*⁴, and rigid with the sleeve *k*⁵ on the stem *b* of the front wheel. Said sleeve *k*⁵ is not fastened to the stem *b*, but is free to turn thereon. The tongue *L* is connected by a 5 horizontal bolt *k*⁶ with the arm *k*⁷ which rigidly connects or unites the rack *k*⁸ with the sleeve *k*⁵, whereby the latter must turn when the tongue swings sidewise, although the tongue can swing up and down. The 10 arm *k*¹, being locked to the rack *k*⁸ by the catch *k*⁴, must also turn when the tongue swings sidewise, and hence the front wheel turns to right and left with the tongue. The angle of the tongue, relative to the wheel *B*, 15 can be changed at will, by releasing the catch *k*⁴, and in this way the front wheel can be positioned to suit the requirements. The rear wheel is held against movement to right or left while the plow is traveling 20 straight ahead, but the side swing of the tongue releases the rear wheel, to a certain extent, because of the angular position of the slot *k* when the tongue is swung to one side. Thus the wheels *B* and *C* can have the same 25 or different angles, and the front wheel can be turned to either side, while the tongue remains straight; or, if necessary, the tongue can be swung to one side without disturbing the position of the wheels. The said tongue, 30 however, is fixed to the member *k*⁸, which latter engages the bolt *k*⁶, and the adjustment is obtained without disturbing the connection between the said member *k*⁸ and the tongue. Thus the draft pin or bolt *k*⁶ is always 35 at right angles to the tongue, or at some fixed angle thereto.

Suitable provisions *e*¹ are made at the end of the beam *e* for the draft, the plow being what is ordinarily known as a single bail 40 plow, there being no bail for the front end of the beam. Also, and in the usual manner, a spring *N* connects the frame with the bail *E*, thereby assisting in lifting the plow, and the driver's seat *O* is in the usual position. 45

As shown in Figs. 13, 14 and 15, the construction is substantially the same as that previously described. In this case, however, the arm *h*² is provided with a hand 50 lever *M*, and the lever *H* (previously described) is provided with a rack *m*, said lever *M* having a catch *m*¹ for engaging said rack. This takes the place of the arm *h*, holes *h*¹ and bolt *h*³ (previously described), and in addition enables the operator to 55 change the angle of the arm *h*² while the plow is in operation. The said rack has three notches *m*² which correspond to the said three holes *h*¹, and which afford intermediate and extreme up and down positions for the bail portion *f*¹, relative to the land-side wheel. In other words, the hand lever *M* can be employed for controlling the land-side wheel independently of the bail and 60 plow, whenever this is found necessary or 65

desirable. Ordinarily, however, the lever *H* is sufficient for all purposes and the lever *M* is provided merely to satisfy the requirements in exceptional cases.

The hand lever *H* is not only a depth 70 regulating lever, of course, but is also a leveling device as well, inasmuch as the body frame is supported at a fixed height on the front and rear furrow wheels, and whatever leveling action takes place is accomplished by the control exercised by said hand lever over the land-side wheel. When the plow is set at a lower depth the land-side 75 wheel rises relative to the frame, and when the plow is set for a shallow furrow the said wheel takes a position lower down relative to said frame. This, of course, tends to keep the frame level, and to that extent the wheeled plow is in one sense self-leveling, inasmuch as the leveling action is not 80 dependent upon a separate operation, but to the contrary is included in the raising and lowering of the plow by the rocking of the 85 front bail thereof.

With further respect to the arrangement 90 whereby the bottom of the furrow is kept level, it will be understood, of course, that merely keeping the frame level does not, in a wheeled implement of this character, necessarily mean that the bottom of the furrow 95 will be level. Whether the bottom of the furrow is level, depends, of course, upon whether the cutting edge of the plowshare is maintained in a horizontal plane. Referring to Fig. 1, and as is well known, this 100 cutting edge extends obliquely to the line of travel, when the plow is viewed from above, and it follows that a tilting of the plow beam on the bail will so change the position of this cutting edge that the furrow 105 is no longer level. As stated, therefore, the level condition of the bottom of the furrow does not necessarily result from merely keeping the wheeled frame level, and is dependent upon a coöperation of the bail and the 110 offset axle, as well as the action of the rear supporting mechanism for the plow-beam. With the herein shown and described construction, and as previously stated, the hand lever *H* is something more than a depth 115 regulating lever, inasmuch as the frame *A* is supported at a fixed height on the wheels *B* and *C*, whereby the said hand lever must also control the bail and offset axle in a manner to insure a level furrow bottom for 120 all depth adjustments of the plow. It is also true, for the reasons previously given, that the rear support *J* and its link *j*² contribute to the leveling of the plow to insure a level bottom for the furrow, inasmuch as this is something that is dependent to some extent upon the position of the plow-beam on the bail *F*; for while the offset axle might keep the frame level during up and down adjustment of the plow to vary the 125 130

- depth, still it might be found that the bottom of the furrow was not level because of the tilted position of the plow-beam on the bail—that is to say, because of the fact that 5 the cutting edge of the plowshare was not traveling in a horizontal plane. As stated, therefore, the keeping of the bottom of the furrow level is something that depends upon the proper coöperation of the bail and offset 10 axle and rear swinging support for the plow-beam; for, in order to keep the cutting edge of the plow in a horizontal plane, at any desired depth, and with different degrees of suck for the plow, it is necessary that the 15 tilting of the frame about a longitudinal axis be controlled in the right manner, and that the tilting of the plow about a transverse axis be also controlled for the purpose of keeping the cutting edge of the plowshare 20 in a horizontal plane. With the construction shown and described, these elements are desirably so arranged that they coöperate to keep the plow level, thereby insuring a level bottom for the furrow regardless of 25 the depth thereof, and thus the hand lever H is employed for rocking the bail and axle to vary the depth in a wheeled plow which, because it has no special or separate hand lever or other device for leveling purposes, 30 is practically self leveling in character; for, with the construction shown and described, there is no adjustment of the plow, other than the rocking of the front bail to vary the depth, which might tend to disturb the 35 level condition of the plow-bottom, and it follows that whatever leveling is done must be accomplished by the said hand lever H as something incidental to its primary function of regulating the depth.
- 40 In order to plow deeper, the wheel D must move upward relative to the furrow, and to plow a more shallow furrow the said wheel must move downward relative to said frame, which is necessary in addition to the up and 45 down adjustment of the beam in the frame, as the plow bottom must always be level with the bottom of the front and rear furrow wheels, and the land wheel must always travel on the high or unplowed ground.
- 50 The element F is commonly termed a bail, but in effect it is a rock shaft or crank shaft, and hence a crank shaft of any suitable character can be employed for this purpose.
- For the broader purpose of my invention, 55 I do not limit myself to any particular form of plow, nor to any particular number of bails for the plow beam. These are things that can be changed or modified without departing from the spirit of my invention.
- 60 Also, I do not limit myself to the exact construction shown and described.
- What I claim as my invention is:
1. In a wheeled implement, a frame, a bail mounted to turn in bearings on said frame, a beam on said bail, mechanism for

operating said bail to raise and lower the implement, an adjustable connection between said mechanism and bail, having provisions to change the relation between said mechanism and bail, for regulating the position 70 of said beam to vary the working depth of said implement, front and rear furrow wheels for said frame, and a land-side wheel for said bail, subject to control by adjustment of said connection. 75

2. In a wheeled implement, a frame, a bail mounted to turn in bearings on said frame, a beam on said bail, adapted to be raised and lowered by rotation thereof, mechanism for operating said bail to raise 80 and lower the implement, an adjustable connection between said mechanism and bail for regulating the position of said beam to vary the working depth of said implement, front and rear furrow wheels for said frame, 85 and a land-side wheel for said bail, said connection including a rack loose on said bail, an arm fixed on said bail, and means for releasably engaging the rack, carried on said arm. 90

3. In a wheeled implement, a frame, a bail mounted to turn in bearings on said frame, a beam on said bail, adapted to be raised and lowered by rotation thereof, mechanism for operating said bail to raise 95 and lower the implement, an adjustable connection between said mechanism and bail having provisions to change the relations between said mechanism and bail, for regulating the position of said beam to vary the 100 working depth of said implement, front and rear furrow wheels for said frame, and a land-side wheel for said bail, a hand lever for said connection, fixed on the bail, and a pair of foot levers for operating said mechanism, one for lifting and the other for depressing the implement. 105

4. In a wheeled implement, a frame, a bail mounted to turn in bearings on said frame, a beam on said bail, adapted to be raised and lowered by rotation thereof, mechanism for operating said bail to raise 110 and lower the implement, an adjustable connection between said mechanism and bail, having provisions to change the relations between said mechanism and bail, for regulating the position of said beam to vary the working depth of said implement during the operation thereof, front and rear furrow 115 wheels for said frame, and a land-side wheel for said bail, said land-side wheel having an axle, an arm for said axle, mounted on said bail, and an adjustable connection between said arm and bail. 120

5. In a wheeled implement, a frame, a bail mounted to turn in bearings on said frame, a beam on said bail, adapted to be raised and lowered by rotation thereof, mechanism provided with lifting and depressing levers for operating said bail to 125 130

- raise and lower the implement, an adjustable connection between said mechanism and bail for regulating the position of said beam to vary the working depth of said implement, front and rear furrow wheels for said frame, and a land-side wheel for said bail, said furrow wheels mounted to travel at a fixed depth below said frame, a plow for said beam, a hand lever arranged for controlling said connection, and an offset axle for said land-side wheel, whereby the plow is leveled and the working depth thereof controlled entirely by said land-side wheel and bail.
15. 6. In a wheeled implement, a frame, a bail mounted to turn in bearings on said frame, a beam on said bail, adapted to be raised and lowered by rotation thereof, mechanism for operating said bail to raise and lower the implement, an adjustable connection between said mechanism and bail for regulating the position of said beam to vary the working depth of said implement, front and rear furrow wheels for said frame, 25 and a land-side wheel for said bail, said connection including a sleeve loose on said bail, a rack secured on said sleeve, a hand lever secured to the bail, means for releasably engaging said rack, carried on said lever, an arm rigid with the other end of said sleeve, and a link connecting said arm with said mechanism.
7. In a wheeled implement, a frame, a bail mounted to turn in bearings on said frame, a beam on said bail, adapted to be raised and lowered by rotation thereof, mechanism for operating said bail to raise and lower the implement, an adjustable connection between said mechanism and bail, 35 means to control said connection and rock said bail for regulating the position of said beam to vary the working depth of said implement, front and rear furrow wheels for said frame, and a land-side wheel for said bail, said connection including an element secured to the bail, and said land-side wheel having an axle arm loose on said bail, adjustably connected with said element.
8. In a wheeled implement, a frame, a bail mounted to turn in bearings on said frame, a beam on said bail, adapted to be raised and lowered by rotation thereof, mechanism for operating said bail to raise and lower the implement, an adjustable connection between said mechanism and bail for regulating the position of said beam to vary the working depth of said implement, front and rear furrow wheels for said frame, and a land-side wheel for said bail, said 50 connection including an arm on said bail, a link connecting the arm with said mechanism, a stop carried by the frame, and means rigid with said arm for engaging said stop to limit the downward motion of said beam.
65. 9. In a wheeled implement, a body frame, an implement carrying a bail thereon, a land-side wheel having an off-set axle on said bail, mechanism connected with and arranged for rocking said bail to raise and lower the implement, a connection between 70 said mechanism and bail, a stationary stop carried on the frame, a movable means connected with the bail and arranged for engaging said stop to limit the rotation of said bail in one direction, and devices to rock the 75 bail while said means is retained in engagement with said stop.
10. In a wheeled implement, a frame, a bail thereon, mechanism for operating said bail, a connection between said mechanism and bail, a stationary stop carried on the frame, and movable means connected with the bail and arranged for engaging said stop to limit the rotation of said bail, said connection including an arm on said bail, a link 80 connecting the arm with said mechanism, and said means being rigid with said arm.
11. In a wheeled implement, a frame, a bail thereon, mechanism for operating said bail, a connection between said mechanism and bail, a stationary stop carried on the frame, and movable means connected with the bail and arranged for engaging said stop to limit the rotation of said bail, said connection including a plurality of pivoted 85 joints, and said means being adjustable to take up looseness in said joints, by pressure on said stop, serving thereby to relieve said connection of the strain when the implement is in the ground.
12. A wheeled implement comprising a raising and lowering mechanism therefor, adapted to hold the implement down, a frame, a bail operated by said mechanism and mounted on said frame to support the 105 implement, means on said frame to engage said mechanism for reducing the strain thereon and preventing looseness thereof from allowing the implement to ride out of the ground in hard spots when said mechanism is in position to hold the implement down, and devices to rock said bail while said mechanism remains in said position.
13. A wheeled implement comprising a raising and lowering mechanism therefor, 110 adapted to hold the implement down, a frame, a bail operated by said mechanism and mounted on said frame to support the implement, means adapted to engage said mechanism for reducing the strain thereon and preventing looseness thereof from allowing the implement to ride out of the ground in hard spots when said mechanism is in position to hold the implement down, and devices to rock said bail while said mechanism remains in said position, said means being adjustable to take up slack in 115 said mechanism and thereby insure the proper operation thereof.
14. A wheeled implement comprising a 120

raising and lowering mechanism therefor, adapted to hold the implement down, a frame, a bail operated by said mechanism and mounted on said frame to support the implement, means adapted to engage said mechanism for reducing the strain thereon and preventing looseness thereof from allowing the implement to ride out in hard spots when said mechanism is in position to hold the implement down, and devices to rock said bail while said mechanism remains in said position, said means including a stationary stop carried by said frame, a movable element connected with said mechanism, and an adjustable set screw on said element for engaging said stop.

15 16. In a wheeled implement, a frame, wheels therefor, an implement beam disposed in position to move up and down in the frame, raising and lowering apparatus for said beam, having provisions for varying the working depth of the implement in the ground, a rear supporting element having its rear end pivotally supported on the frame, a bracket on the beam, and a link pivoted upon and depending from the forward end of said element, having its lower end pivotally connected with said bracket, coöperating with said element and apparatus to maintain the point of said implement below the heel thereof for all depths in the ground, said link permitting the beam to tilt up behind while in lowered position, said apparatus having a foot lever for the operation thereof.

20 17. In a wheeled implement, a frame, wheels therefor, an implement beam disposed in position to move up and down in the frame, raising and lowering apparatus for said beam, having provisions for varying the working depth of the implement in the ground, a rear supporting element having its rear end pivotally supported on the frame, a bracket on the beam, a link pivoted upon and depending from the forward end of said element, having its lower end pivotally connected with said bracket, coöperating with said element and apparatus to maintain the point of said implement below the heel thereof for all depths in the ground, and means fixed on said frame to limit the downward movement of said element, said link permitting the beam to tilt up behind while in lowered position, fixed on the link, said apparatus having a foot lever for the operation thereof.

25 18. In a wheeled implement, a frame, wheels therefor, an implement beam disposed in position to move up and down in the frame, raising and lowering apparatus for said beam, having provisions for varying the working depth of the implement in the ground, a rear supporting element having its rear end pivotally supported on the frame, a bracket on the beam, a link

pivoted upon and depending from the forward end of said element, having its lower end pivotally connected with said bracket, coöperating with said element and apparatus to maintain the point of said implement below the heel thereof for all depths in the ground, and means for limiting the relative movement of said link and element, said link permitting the beam to tilt up behind while in lowered position, said apparatus having a foot lever for the operation thereof.

30 19. In a wheeled implement, a frame, wheels therefor, an implement beam disposed in position to move up and down in the frame, raising and lowering apparatus for said beam, having provisions for varying the working depth of the implement in the ground, a rear supporting element having its rear end pivotally supported on the frame, a bracket on the beam, a link pivoted upon and depending from the forward end of said element, having its lower end pivotally connected with said bracket, coöperating with said element and apparatus to maintain the point of said implement below the heel thereof for all depths in the ground, and means on said frame to engage said element, said link permitting the beam to tilt up behind while in lowered position, said apparatus having a foot lever for the operation thereof.

35 20. In a wheeled implement, a frame, wheels therefor, an implement beam disposed in position to move up and down in the frame, raising and lowering apparatus for said beam, having provisions for varying the working depth of the implement in the ground, a rear supporting element having its rear end pivotally supported on the frame, a bracket on the beam, and a link pivoted upon and depending from the forward end of said element, having its lower end pivotally connected with said bracket, coöperating with said element and apparatus to maintain the point of said implement below the heel thereof for all depths in the ground, said point and heel being the front and rear ends of a plow on said beam, said apparatus including a supporting bail for said beam, coöperating with said link and element to cause the plow to leave the ground point first, said link permitting the beam to tilt up behind while in lowered position, said apparatus having a foot lever for the operation thereof.

40 21. In a wheeled implement, a frame, wheels therefor, an implement beam disposed in position to move up and down in the frame, raising and lowering apparatus for said beam, having provisions for varying the working depth of the implement in the ground, a rear supporting element having its rear end pivotally supported on the frame, a bracket on the beam, and a link

- pivoted upon and depending from the forward end of said element, having its lower end pivotally connected with said bracket, coöperating with said element and apparatus to maintain the point of said implement below the heel thereof for all depths in the ground, said point and heel being the front and rear ends of a plow on said beam, said link permitting the beam to tilt up behind 10 while in lowered position; said apparatus including means coöperating with said link and element to cause the plow to enter and leave the ground point first, and having a foot lever for operation thereof.
21. In a wheeled plow, a rear supporting mechanism for the plow beam, operator controlled raising and lowering means having an adjustable connection with the plow beam for varying the depth of the furrow during 20 the plowing operation and coöperating with said mechanism to cause the plow to always enter the ground point first, devices to control said connection at will and thereby vary the depth without disturbing said mechanism, and a wheeled body frame for supporting said mechanism and said means in position to hold the plow in the ground or in raised position.
22. In a wheeled plow, a rear supporting mechanism for the plow beam, operator controlled raising and lowering means coöperating with said mechanism to cause the plow to enter the ground point first, and a wheeled body frame for supporting said mechanism and said means in position to hold the plow in the ground or in raised position, said mechanism comprising a pivotally supported member disposed with its free end extending upward and forward, 30 and a supporting link pivoted at opposite ends thereof between the plow beam and the free end of said member, to permit tilting motion of the plow, and devices to hold said means stationary on the frame during said tilting motion.
23. In a wheeled plow, a rear supporting mechanism for the plow beam, operator controlled raising and lowering means coöperating with said mechanism to cause the plow to enter the ground point first, and a wheeled body frame for supporting said mechanism and said means in position to hold the plow in the ground or in raised position, said mechanism comprising a support pivoted on said frame, a link pivoted upon and depending from the free end of said support, means for limiting the relative movement of said link and support, and a pivot for connecting the lower end of said link with the plow beam to permit tilting motion of the plow, and devices to hold said means stationary on the frame during said tilting motion.
24. In a wheeled implement, a foot lift mechanism therefor, having an adjustable connection with the implement, providing means for raising and lowering the implement, serving by the adjustment thereof to regulate the working depth of said implement, said connection including a hand lever 70 for adjusting the implement up and down, relative to said mechanism, while the latter remains stationary, and means for locking and unlocking the connection between the lever and said mechanism, said lever having 75 a landside wheel axle rigid therewith.
25. In a wheeled implement, a foot lift mechanism therefor, having an adjustable connection thereto, providing means for raising and lowering the implement, serving 80 by the adjustment thereof to regulate the working depth of said implement, said connection to the implement including a bail operable by said mechanism to raise and lower the implement, and means for controlling said connection to vary the depth, front and rear furrow wheels, and a frame supported at a fixed height at front and rear thereof by said wheels.
26. A wheeled implement comprising raising and lowering means provided with an adjustable connection with the implement to vary the working depth thereof, a hand lever for controlling said connection, a leveling mechanism having a lever and landside wheel controlled by said lever, front and rear furrow wheels, a frame supported at a fixed height at front and rear thereof by said front and rear wheels, but at a variable height by said land-side wheel, and 85 a foot lever for operating said means.
27. A wheeled implement having an offset axle, a land-side wheel on said axle, a lever arranged for controlling said wheel, a bail on which said lever is mounted, means 90 for rocking said bail to raise and lower the implement, and an adjustable connection between said axle and lever, said connection including a rack rigid with said lever, a hand lever rigid with said axle, and means 95 on said last mentioned lever for adjustably engaging said rack.
28. A wheeled implement having an offset axle, a land-side wheel on said axle, a lever arranged for controlling said wheel, 100 an adjustable connection between said axle and lever, a rotary element rigid with said lever, means for rocking said element to raise and lower the implement, a rack, means engaging said rack to prevent said 105 element from turning, carried on said lever, and a hand lever for operating said adjustable connection.
29. A wheeled implement comprising a rotary element, means for rocking said element to raise and lower the implement, an offset axle, a lever rigid with said element, means for holding said element against turning, an adjustable connection between said element and axle, a hand lever for operating 110

said connection, and a land-side wheel on said axle.

30. In a wheeled plow, a bail, a beam on said bail, a plow on said beam, a foot lift mechanism for rocking the bail to raise and lower the plow, means for rocking said bail to vary the furrow depth, and devices for holding said means in the different positions necessary for different depths.

10 31. In an agricultural implement, the combination of wheels and a body frame supported thereon, a bail mounted on said frame, an implement beam supported on said bail to shift up and down in said frame, 15 means to support the rear portion of said beam on said frame, a foot-lift mechanism for rocking said bail to raise and lower the implement out of and into the ground, a hand lever connected for rocking said bail, 20 an adjustable connection interposed between said hand lever and said mechanism to regulate the depth of said implement in the ground, and means on the frame to hold said mechanism in the different positions 25 thereof.

32. In an agricultural implement, the combination of wheels and a body frame supported thereon, a bail on said frame, an implement beam mounted on said bail to shift 30 up and down in said frame, a member pivoted on said frame in rear of said beam, a link pivoted on said member and depending therefrom, a pivot between the said beam and the lower end of said link, said link permitting 35 said beam to tilt forward or backward on said bail, and means on said member to limit the movement of said link relative thereto.

33. In an agricultural implement, the combination of wheels and a body frame supported thereon, a bail mounted on said frame, an implement beam supported on said bail to shift up and down in said frame, 40 means to support the rear portion of said beam on said frame, a foot-lift mechanism for rocking said bail to raise and lower the implement out of and into the ground, a hand lever connected for rocking said bail, an adjustable connection interposed between 45 said hand lever and said mechanism to permit regulation of the depth of said implement in the ground, and means on the frame to hold said mechanism in the different positions thereof, said bail having an offset 50 landside axle for one of said wheels, and said implement being a plow carried on the rear end of said beam.

34. In an agricultural implement, the combination of wheels and a body frame supported thereon, a bail on said frame, an implement beam mounted on said bail to shift 60 up and down in said frame, a member pivoted on said frame in rear of said beam, a link pivoted on said member and depending therefrom, a pivot between the said beam

and the lower end of said link, said link permitting said beam to tilt forward or backward on said bail, and means on said member to limit the movement of said link relative thereto, said bail having an offset landside axle for one of said wheels, and said implement being a plow carried on the rear end of said beam.

35. In an agricultural implement, the combination of wheels and a body frame supported thereon, a bail mounted on said frame, an implement beam supported on said bail to shift up and down in said frame, means to support the rear portion of said beam on said frame, a foot-lift mechanism for rocking said bail to raise and lower the implement out of and into the ground, a hand lever connected for rocking said bail, an adjustable connection interposed between said hand lever and said mechanism to permit regulation of the depth of said implement in the ground, and means on the frame to hold said mechanism in the different positions thereof, said frame having the front and rear ends thereof supported at a fixed 90 height by two of said wheels.

36. In an agricultural implement, the combination of wheels and a body frame supported thereon, a bail on said frame, an implement beam mounted on said bail to shift up and down in said frame, a member pivoted on said frame in rear of said beam, a link pivoted on said member and depending therefrom, a pivot between the said beam and the lower end of said link, said link permitting said beam to tilt forward or backward on said bail, and means on said member to limit the movement of said link relative thereto, said frame having the front and rear ends thereof supported at a fixed 95 height by two of said wheels.

37. In an agricultural implement, the combination of a body frame, wheels for supporting said frame, an implement beam supported on said frame to shift up and down relative thereto, a foot-lift mechanism arranged for controlling said beam to raise and lower the implement out of and into the ground, and means including a hand lever for adjusting the beam relative to said mechanism and for thereby changing the depth of the implement in the ground, said lever controlling one of said wheels to keep the implement level.

38. In an agricultural implement, the combination of a body frame, wheels for supporting said frame, an implement beam supported on said frame to shift up and down relative thereto, a foot-lift mechanism arranged for controlling said beam to raise 120 and lower the implement out of and into the ground, and means including a hand lever for adjusting the beam relative to said mechanism and for thereby changing the depth of the implement in the ground, said 125 130

lever controlling one of said wheels to keep the implement level, and said mechanism being connected to control the same wheel when the implement is raised and lowered.

- 5 39. In an agricultural implement, the combination of a body frame, wheels for supporting said frame, an implement beam supported on said frame to shift up and down relative thereto, a foot-lift mechanism 45 arranged for controlling said beam to raise and lower the implement out of and into the ground, and means including a hand lever for adjusting the beam relative to said mechanism and for thereby changing the 50 depth of the implement in the ground, said lever controlling one of said wheels to keep the implement level, and said frame being supported at a fixed height by the other wheels.
- 10 40. In a wheeled plow, a bail, a beam on said bail, a plow on said beam, a foot-lift mechanism for rocking the bail to raise and lower the plow, means for rocking said bail in either direction to vary the furrow depth, 55 thereby to either increase or reduce the depth of the furrow at will, and devices for holding said means in the predetermined positions necessary for different depths, said mechanism being stationary on the frame 60
- 15 40. during the operation of said means, and a land-side wheel having an off-set axle controlled by said means.
- 20 41. In a wheeled plow, a bail, a beam on said bail, a plow on said beam, a foot lift 65 mechanism for rocking the bail to raise and lower the plow, a frame whereon said bail and mechanism are mounted, means for rocking said bail in either direction to vary the furrow depth, thereby to either increase or reduce the depth of the furrow at will,
- 25
- 30
- 35
- 40

and devices for holding said means in the predetermined positions necessary for different depths, said mechanism being stationary on the frame during the operation of said means, a land-side wheel having an off-set axle controlled by said means, and a rear support for said beam, said support coöperating with said bail and axle to keep the bottom of the furrow level.

42. In a plow, the combination of a crank-member, an implement supported by said member, mechanism for operating said member about a horizontal axis to raise and lower the plow, means traveling on the ground to support said member, a depth-regulating hand-lever mounted to swing forward and backward at its upper end, connected at its lower end to raise and lower said implement by changing the relation thereto of said crank-member, thereby to vary the working depth of the implement in the ground, another hand-lever arranged for leveling the implement, and devices to hold said levers in different positions.

43. In a plow, the combination of a plow-beam, means including a wheel-supported-crank mounted to turn in bearings, means to support said plow-beam on the crank, mechanism to partially revolve said crank in said bearings to either raise or lower said plow-beam, and means including a hand-lever to partially revolve said crank in said bearings to either raise or lower the plow-beam.

Signed by me at Janesville, Wis., this 10th day of September, 1913.

ALVARO S. KROTZ.
